United States Patent Office.

D. C. RICHARDSON, OF WELDON, NORTH CAROLINA.

Letters Patent No. 70,120, dated October 22, 1867.

IMPROVEMENT IN COTTON AND CORN-PLoughs.

The Schedule referred to in these Letters Patent and making part of the same.

TO ALL WHOM IT MAY CONCERN:

Be it known that I, D. C. RICHARDSON, of Weldon, Halifax county, North Carolina, have invented certain new and useful improvements in Double-Shovel Ploughs or Cultivators; and I do hereby declare that the following is a full and exact description of the same, reference being had to the annexed drawings, and to the letters of reference marked thereon, in which—

Figure 1 is a perspective view.

Figure 2 is a plan view of the bottom of the plough.

Figure 3 is a side elevation—

Like letters representing the same features in the several figures.

A A are the handles, connected with the shoe S in any convenient manner. B is the beam, to which the standard C is attached, and having a plate, D, on the lower part cast with said standard. To the lower part is attached the tooth E, which may be adjusted by a bolt, nut, and slot, so as to be set further forward or backward, as occasion or necessity requires. To the upper portion of the plate are attached wings W W, one on each side, which are adjustable, and can be easily removed in order, when occasion requires, that wings of different size may be used, so that my invention can the more usefully accommodate itself to the crop at the various stages of its advancement. S is the shoe, curved at its forward end, and bolted to the standard. There is a slot, a, in the shoe S, in which are inserted, and with the proper means of adjustment, other wings R R, and secured in slots held by wedges, or in any other convenient manner.

Having thus fully described my invention, and its method of construction, what I claim as new, and desire to secure by Letters Patent, is—

1. The plate D cast with the standard, in combination with the adjustable tooth, substantially as described.
2. I claim the plate D cast with the standard, in combination with the adjustable wings W W, substantially as described, for the purposes set forth.
3. The shoe S, having in rear of the mould-plate a slot, a, in which wings R R of different sizes and form can be secured, when the same is in combination with wings W W, the whole constructed and combined substantially as set forth.
4. I claim the devices embraced in the foregoing claims, when the same are arranged in the manner described and for the purpose set forth.
